(57) **CLAIM**

I claim the ornamental design for a cell storage container, as shown and described.

DESCRIPTION

FIG. 1 is a front perspective view of a cell storage container, showing my new design;

FIG. 2 is a rear perspective view thereof;

FIG. 3 is a front elevational view thereof;

FIG. 4 is a rear elevational view thereof;

FIG. 5 is an enlarged top plan view thereof;

FIG. 6 is an enlarged bottom plan view thereof;

FIG. 7 is a right side elevational view thereof;

FIG. 8 is a left side elevational view thereof;

FIG. 9 is an enlarged cross-sectional view taken in the direction of line 9-9 of FIG. 3; and,

FIG. 10 is an enlarged cross-sectional view taken in the direction of line 10-10 of FIG. 3.

In the drawings, the equal-length broken lines depict unclaimed portions of the cell storage container that form no part of the claimed design. The dash-dot-dash broken lines define the boundaries of the claim. All broken lines form no part of the claimed design.
